UNITED STATES PATENT OFFICE.

THOMAS G. HANEY, OF NEW LONDON, CONNECTICUT.

COTTON-BLEACHING APPARATUS.

1,255,161.

Specification of Letters Patent. Patented Feb. 5, 1918.

Application filed June 18, 1917. Serial No. 175,253.

To all whom it may concern:

Be it known that I, THOMAS G. HANEY, a citizen of the United States, residing at New London, in the county of New London and State of Connecticut, have invented certain new and useful Improvements in Cotton-Bleaching Apparatus, of which the following is a specification.

This invention relates to a cotton-bleaching apparatus. I have selected the title given as a matter of convenience for really the bleaching of the product is but a step or incident in the procedure. In the treatment of cotton it is initially washed and is subsequently baled. At an intermediate point, however, it is subjected to a bleaching action. One of the primary motives I have in view is the provision of apparatus by which this bleaching can be accomplished in a quick and highly satisfactory manner, and in a readier and quicker way than is now possible.

In the drawings accompanying and forming part of the present specification I have shown in detail a form of apparatus involving the invention, and this I will set forth fully in the following description. As will be obvious I am not restricted to this structure. I may depart therefrom in various ways within the scope of the invention defined by the claims following said description.

Referring to said drawings:

Figure 1 is a plan view of apparatus involving the invention.

Fig. 2 is a side elevation.

Fig. 3 is an elevation as seen from the left in Fig. 2.

Fig. 4 is an elevation as seen from the left in Fig. 3 of a portion of the carriage.

Fig. 5 is a detail view of a vat and certain of its adjuncts, and

Fig. 6 is an elevation as seen from the right in Fig. 5.

Fig. 7 is a diagram illustrative of a drive for an overhead carriage.

Like characters refer to like parts throughout the several views which are on different scales.

The cotton after it is initially prepared as by washing is discharged into a suitable carrier such for instance as a traveling carriage where it is subjected to certain preliminary treatments such as shredding, and after this is conveyed into a bleaching de-

vice where as may be inferred it is bleached. I provide several of these bleaching devices, and a carriage provided with certain necessary mechanism, the carriage being common to the several bleaching devices. As shown there are several of such bleaching devices, such as those denoted respectively in a general way by 2, 3, 4 and 5 in Fig. 1. Although there are four of such bleaching devices, this may not in all cases be necessary. For facility it is desirable to employ several although there may be instances when one is only required, and in this event the carrier which supplies them with the cotton or equivalent product may be stationary. A carrier such as meets my conditions is that denoted in a general way by 6 and will be hereinafter described in detail.

As the bleaching devices are all the same in construction a detailed description of one of them for instance that denoted by 2 as shown for illustration in Figs. 2 to 6 inclusive will apply to the others. Said bleaching device comprises a vat or tank such as that denoted in a general way by 7 and 80 which is usually stationary. It may as shown be sunk for a short distance into a floor or other support as 8. It is adapted to contain a bleaching solution which may be any one of those now used. The tank 7 85 supports a drum as 9 having outwardly extending coaxial gudgeons or studs 10 sustained by pillow blocks or equivalent bearings as 11 on the sides of the vat or tank 7. The peripheral portion of the drum or rotary vessel 9 is perforated and has openings covered by doors as 12. By opening one of these doors the drum 9 may be supplied with the cotton to be bleached, and when the requisite amount is introduced thereinto the door is closed and the drum then rotated as will hereinafter appear, to cause the bleaching solution to reach every part of the mass of cotton within the drum, the liquid circulating through the mesh of the peripheral or circumferential portion of the drum. After the necessary amount of cotton or equivalent substance has been supplied into the drum, the latter is subjected to rotation when the bleaching commences and at the conclusion of the requisite time the drum with its contents is elevated bodily from the bleaching solution tank 7, so that the cotton may drain. When the cotton is drained, it is discharged from the drum by opening 110

both doors 12, onto the floor or otherwise disposed of to permit it to dry for preliminary or subsequent and final treatment.

The drum 9 may be rotated in any desirable manner, although the means shown for this purpose will now be described. The ends of the drum are furnished with circular racks 13 in mesh with pinions as 14 fastened to the shaft 15 supported for rotation by bearings as 16 upon the side walls of the vat or wall 7 near the outer side thereof. As shown the shaft 15 has fixed to it a worm gear 16' in mesh with the worm 17 on the shaft 18 connected as by gearing 19 with the shaft 20 provided with the pulleys 21, 22 and 23, the intermediate pulley 22 being loose on the shaft 20, while the two outside pulleys 21 and 23 are tight with said shaft. Coöperative with the pulleys 21, 22 and 23 is the belt 25 driven by a suitable source of power and shown as being on the intermediate pulley 22. By shifting the belt through a suitable shifter such as that denoted in a general way by 26 onto either of the pulleys 21 or 23, the shaft 20 will be driven to effect through the intervention of the described parts, the rotation of the drum or cylinder 9 and the resultant subjection of the mass of cotton therein, to the action of the bleaching agent. It will be assumed that the drum 9 of the bleaching device 2 has been filled with the requisite quantity of cotton and that the doors 12 are as a result closed. In this event the drum will be caused to rotate through the action of the parts already described to bleach the material in the drum. When the bleaching is finished the drum with its contents is elevated from the tank and the liquid drained therefrom falling into the tank. After the draining operation the drum is shifted from over the tank and the doors 12 opened, so that the contents of the drum can be discharged therefrom onto the floor or otherwise.

As I have already noted there are four of such bleaching devices, and they are supplied in succession with the necessary cotton as by the carriage 6. As shown this carriage involves in its make-up a supporting body such as 30, provided with wheels as 31 to travel on the rails 32 adjacent to the tanks 7 of the row of bleaching devices 2. The rails constituting a suitable track are in fact virtually parallel with the tanks. The power for driving the different parts on the carriage 6 may be of any convenient nature, the electric motor 33 supported by the base portion of the frame of the carriage 60 answering in this particular. The necessary current for the operation of the motor 33 may be supplied in any desirable manner as will be clear. The body of the carriage 6 is denoted by 36 and it is practically of hopper-like form. The inner side of the

hopper-like body 36, it will be seen is higher than the outer side, see for instance Fig. 2. In the hopper-like body and parallel to the rear inclined wall thereof is the endless conveyer or belt 37. The forward run of this 70 endless conveyer 37 and the forward wall of the hopper-like body 36 jointly present a V-shaped pocket into which the cotton to be bleached is deposited. The armature shaft of the motor 33 is equipped with a pulley 38 75 connected as by the belt 39 with the pulley 40 on the shaft 41, this shaft in turn carrying the pulley 42 connected by the belt 43 with the pulley 44 on the shaft 45, the latter carrying a second pulley 46 connected by 80 the cross belt 47 with the pulley 48 on the lower shaft of the conveyer 37, the forward or active run of which moves in the direction of the arrow applied thereto in Fig. 2. The shaft 45 extends between and is supported 85 by the side walls of the hopper-like body 36. The shaft 41 is also similarly supported for reasons that will hereinafter appear. It will be clear, therefore, that if the motor 33 be started, the forward run of the endless 90 conveyer or belt 37 will be moved in the direction of the arrow applied thereto in said Fig. 2 so as to elevate the mass of cotton sustained thereby. The cotton on the conveyer 37 is in mass. It is given first a primary treatment and then a secondary treatment as will hereinafter appear before it passes into the drum 9. The cotton is discharged after the secondary treatment from the conveyer 37 onto the upper inclined run 100 of the conveyer 50 supported between the side walls of the extension 51 of the hopper-like body 6. This conveyer 50 has connected with the rear shaft thereof the pulley 52 connected by the belt 53 with a pulley 54 105 on the upper shaft of the main or primary conveyer 37. The cotton is discharged from the secondary conveyer 50 into the necessary circumferential opening of the appropriate drum 9. The sides of the hopper-like body 110 36 are provided with bearings 55 supporting the shaft 56 from which the arms 57 extend inwardly, these arms 57 being connected by a shaft 58 having the bowed fingers 59 which come in contact with the cotton as it travels upward along the forward run of the belt 37 to comb said cotton as the arms 57 are rocked or oscillated as will hereinafter appear. The shaft 56 may as shown be provided with the outwardly extending 115 counterweighted arm 60. Further it is equipped with an arm 61 connected by a rod 62 with the disk 63 rotative with the shaft 45 to which I have already referred. The connection between the rod 62 and the disk 63 is eccentric of the latter, so that as a consequence the rod 62 is given a reciprocal movement in the direction of its length, thus through the described parts to impart a rocking movement to the shaft 58 120 125 130

and the curved fingers 59 projecting therefrom to comb the mass of cotton under the action of the fingers. Just forward of the delivery end of the primary or principal 5 conveyer 37 and between it and the secondary conveyer 50 is a roller 64 between the sides of the hopper-like body 36, the shaft of the roller being provided with a pulley 65 connected by the belt 66 with the pulley 10 67 on the shaft 41. This roller 64 is provided with circumferential projections or teeth 68 which shred or comb the cotton just as it leaves the conveyer 37 and before it passes onto the conveyer 50. The cotton 15 when it passes onto the secondary conveyer 50 is shredded, broken up or divided, so that it is in prime and proper position to enter a drum as 9 in the manner already described. After the drum 9 of say the first 20 bleaching device 2 is supplied with the requisite amount of cotton the carriage 6 is moved along the rails 32 for the supply of cotton to the drum of the second bleaching device and so on, the procedure in view of 25 this circumstance being practically continuous, which is obviously a feature of importance.

After the cotton has been properly bleached the drum containing it will be elevated, the liquid from the drum being permitted to drain therefrom into the vat or tank 7. I have shown a means by which the drums can be properly elevated. Supported above the several bleaching devices 2, 3, 4 35 and 5 is a track 70, this track being in suitable relation with the rails 32. It is generally carried upon the ceiling, although it may be below it. It supports a suitable carriage as 71 from which the endless band or 40 rope 72 is suspended, the band or belt being passed around the pulley 73 and in its loop sustaining another pulley 74. Connected with the band 72 is the cross head 75 from which the arms 76 depend, the arms terminating in hooks 77 which are adapted to engage when desired the gudgeons 10 of a drum 9.

It will be assumed that it is desired to lift a drum 9 from the tank 7 it may occupy. In 50 this case the carriage 71 will be operated to bring it over the desired drum. Said carriage may be operated as follows: It may be equipped with a band wheel 80 on the shaft of which is a traction wheel or wheels 81 55 running on the track or girder 70. Around this band wheel 80 is the band 82 which hangs down and through the manipulation of the band 82, the carriage 71 can be caused to traverse the track, rail or girder 70 to 60 bring the band or rope 72 over the desired

drum 9. The cross-head 75 is shown elevated by dotted lines in Fig. 5, the carriage 71 at this time being over the drum 9. On the carriage 71 is a motor 83 the leads of which are intersected by a switch 84 to the 65 terminals of which are connected the cords or chains 85 and 86 having pull pieces 87. By operating the cord 85 for instance current of one polarity can be sent through the line to lower the crosshead 75, so that the 70 hooks 77 can engage the gudgeons 10 of the drum 9, and when this is done current will be shut off. Then current of opposite polarity will be sent through the motor through the operation of the cord 86 to effect the elevation of the drum 9 over its tank as shown for instance by dotted lines in said Fig. 5. This will permit the cotton in the drum to drain, the drainage liquid passing into the tank. When drainage has proceeded to the 80 requisite extent, the drum will be shifted to the dotted line position in the left in said Fig. 5 so as to bring it from over the tank, and if necessary, the drum will be turned to bring the doors 12 down, and when this is 85 done both doors will be opened to discharge the contents of the drum onto the floor.

What I claim is:

1. The combination of a hopper, an endless conveyer in the hopper, a series of rocking fingers extending across the conveyer between the ends thereof, to comb the material on the conveyer, and a rotary cylinder approximately at the delivery end of the conveyer and extending across the same, said 90 rotary cylinder having a series of peripheral teeth to shred the material approximately at the time the material is discharged from the conveyer.

2. The combination of a hopper, an endless conveyer in the hopper set at an incline, a series of rocking fingers disposed in front of the forward run of the conveyer to comb the material between the ends of the conveyer, a rotary cylinder extending across the 105 conveyer practically at the delivery end thereof and having a series of peripheral projections to shred the material practically at the time it is discharged from the conveyer, a second conveyer to receive the material from the first conveyer, and a bleaching device into which the material is discharged by the second conveyer.

In testimony whereof I affix my signature in the presence of two witnesses.

THOMAS G. HANEY.

Witnesses:
